ATTORNEY.

UNITED STATES PATENT OFFICE.

ARCHIE D. STANDEFORD, OF KANSAS CITY, MISSOURI.

INTERMITTENT DRIVING MECHANISM FOR MOVING-PICTURE FILMS.

1,182,111.

Specification of Letters Patent.

Patented May 9, 1916.

Application filed December 26, 1914. Serial No. 879,053.

To all whom it may concern:

Be it known that I, ARCHIE D. STANDEFORD, a citizen of the United States, residing at Kansas City, in the county of Jackson 5 and State of Missouri, have invented certain new and useful Improvements in Intermittent Driving Mechanism for Moving-Picture Films, of which the following is a specification.

10 My invention relates to improvements in intermittent driving mechanisms for moving picture machines, and one object is to provide a mechanism of this character to prolong the pausing periods and shorten the 15 moving periods of films, over the present practice, to the end that moving pictures may be displayed with greater distinctness and less flicker than heretofore.

20 A further object is to provide intermittent driving mechanism which will be free from jars and vibration in its operation, and consequently will not transmit vibration to the film and thus interfere with the proper projection of the pictures upon a screen.

25 Other objects of the invention will hereinafter appear, and in order that said invention may be fully understood, reference will now be made to the accompanying drawing, in which:

30 Figure 1 is a broken elevation of a moving picture machine provided with my invention. Fig. 2 is a vertical section showing several important features of the invention. Fig. 3 is a vertical section on line III—III 35 of Fig. 1.

Similar reference numerals and letters indicate similar parts throughout the several views.

35 A designates a film which is intermittently driven by the customary sprocket wheel B, fixedly mounted upon a shaft C, journaled in the frame D, having a shaft E also journaled therein. The shaft E may be driven in the usual manner by either a 40 motor, or a crank F. Fixedly-mounted upon the shaft E is a cog wheel G, which drives a pinion H fixed to a large cog wheel I, which drives a pinion J, fixedly-mounted upon a shaft K, provided at one end with a 45 fixedly-mounted cog wheel L. The cog wheel L drives an intermediate cog wheel M, intermeshing with a cog wheel N, mounted upon a shaft O, intermediate the shafts C and K. The shaft O is provided with a 50 fly-wheel P, which insures steady operation 55

of the gear wheels above described. One end of the shaft O is provided with an integral flat-faced transmission member 1, slidably engaged by a coacting flat-faced transmission member 2, fixed upon a shaft 60 3, disposed in axial alinement with the shaft O and arranged to slide longitudinally in its bearings in the frame D.

4 designates a star wheel fixedly-mounted upon the shaft C and provided at one side 65 with a plurality of radial grooves 5.

6 designates a cam wheel, the periphery of which successively contacts the concave margins 7 forming the periphery of the star wheel 4. Said cam wheel 6 has a peripheral 70 cavity 8 at one side to successively admit the passage of the points 9 of the star wheel 4, when the same is rotated step by step by a pin 10, projecting laterally from a peripheral flange 11 at one side of the cam wheel 75 6. The pin 10 successively enters the grooves 5 in the star wheel 4, and rotates the same a distance equal to the distance between the centers of the points 9, each time the pin 10 passes through a groove 5. When the 80 pin 10 passes out of a groove the star wheel 4 is held stationary by the periphery of the cam wheel 6, engaging the registering concave margin 7 of said star wheel, as disclosed by Fig. 3. The cam wheel 6 is fixedly-mounted upon the shaft 3, which latter also carries a fixedly-mounted collar 12, having a peripheral groove 13, to receive a wrist-pin 14 projecting from a disk 15, mounted upon a shaft 16, journaled in bearings 17, 85 and provided at one end with a bevel wheel 18, driven by a bevel wheel 19, fixedly-mounted upon the shaft K. The shaft 16 is provided with a fly-wheel 20, which insures steady operation of said shaft. 90

95 In the practical operation of the invention the parts are so geared and timed, in the present instance, that the cam wheel 6 is shifted to the right (Fig. 1) at every other revolution, so that its pin 10 will miss the star wheel 4. Hence, instead of said star wheel 4 being turned to move the film A one step at every revolution of the cam wheel 6, as is customary, said star-wheel 4 is turned one step only, on each alternate 100 revolution of the cam wheel 6, thereby insuring longer pausing, or exposure periods of the film. Alternate shifting of the cam wheel 6 to the left and the right is accomplished through the intermediacy of the 110

wrist-pin 14 and the collar 12, which latter rotates more rapidly than the former through the intermediacy of the cog wheels L, M and N. As the collar 12 moves to the left and the right it carries the shaft 3 therewith, but said shaft is constantly rotated by the shaft O through the intermediacy of the transmission members 1 and 2, the latter of which slidably engages and is driven by the former. The starting and stopping of the longitudinal movements of the shaft 3 will be attended with little or no shock, because the pin 14 is passing through, substantially, a vertical plane at such times, and consequently the longitudinal speed of the shaft gradually diminishes until it comes to a stop.

While I have shown and described the preferred form of my invention, it is obvious that such changes in the arrangement, combination and proportion of parts may be made as properly fall within the spirit and scope of the claim.

Having thus described my invention, what

I claim and desire to secure by Letters Patent, is:

In combination a sprocket, a gear wheel to drive said sprocket, a second gear wheel to drive the first gear wheel, a shiftable shaft carrying said second gear wheel, means to shift said shaft to carry the second gear wheel out of the path of the first gear wheel and effect intermittent operation of the sprocket, a flat faced transmission member on said shaft, a second flat faced transmission member slidably engaged by the first transmission member, a constantly driven shaft carrying the second transmission member, and a fly-wheel mounted upon the last-mentioned shaft to impart steady motion thereto.

In testimony whereof I affix my signature, in the presence of two witnesses.

ARCHIE D. STANDEFORD.

Witnesses:

F. G. FISCHER,

FRED C. FISCHER.
